UNITED STATES PATENT OFFICE.

JESSE M. YOUNT, OF SAN FRANCISCO, CALIFORNIA.

TWO-PIECE WELDED BRAKE-SHOE.

1,127,841.

Specification of Letters Patent.

Patented Feb. 9, 1915.

Application filed November 10, 1913. Serial No. 800,059.

To all whom it may concern:

Be it known that I, JESSE M. YOUNT, a citizen of the United States, residing at the city and county of San Francisco and State of California, have invented new and useful Improvements in Two-Piece Welded Brake-Shoes, of which the following is a specification.

This invention relates to brake shoes and 10 pertains especially to a metal brake shoe for use on railway cars and the like.

The object of the invention is to provide a simple, practical, economical brake shoe, preferably made of two pieces electrically 15 welded together, one constituting the wearing face and the other a shoe back to fit the shoe head on the brake beam; the shoe face being removable and renewable as it wears down, so that the entire shoe does not have 20 to be thrown away, as is the case with the shoes now generally in use.

The invention consists of the parts and the combination and construction of parts as hereinafter more fully described and 25 claimed, having reference to the accompanying drawings, in which—

Figure 1 is a side elevation of the device. Fig. 2 is a plan view of the same. Fig. 3 is a cross section on line $x-x$ of Fig. 1. 30 A represents the shoe back which is provided with the usual lug 2 to adapt it to be fitted to the usual shoe head or brake beam, not necessary here to be shown. This shoe back A is preferably of steel and is concaved corresponding approximately to the periphery of the car wheel which it is to fit. Where the brake shoe is to be used on flanged wheels the shoe back has a chamfered portion 3 to accommodate the correspondingly formed side of the removable shoe-face plate 4. This shoe-face plate may be of any hard, durable material, such as wrought or cast iron or cast steel, and it is preferred that it at least have a back lining 40 of steel indicated at 5, which is adapted to come up against the steel shoe back A and provide an advantageous welding surface.

Preferably the shoe-face plate 4 is a trifle longer than the shoe back A to provide the 50 end flanges 6 between which the shoe back fits; these end flanges 6 serving to properly center the shoe-face plate on the shoe back and prevent relative end movement of the parts. The shoe-face plate and the shoe 55 back are suitably united together by an

electric weld applied around the ends and sides of the two abutting parts as shown at 7; the shoe back preferably having indented portions 8 along one, or both of its longitudinal edges to form pockets and afford sufficient space for a proper welding of the parts at these plates. This edge welding of the two parts together insures a rigid union and a solid brake shoe with no tendency of the shoe-face plate rocking on its back. Whenever the shoe-face plate is worn down so as to have its usefulness seriously impaired, it is easily knocked off of the shoe back by the blow of a hammer and another shoe-face plate quickly welded in place by means of an appropriate welding tool. The shoe back and shoe-face plate are of substantially the same width in order to give a proper support throughout the whole length and breadth of the shoe-face plate and it is for this reason that the recesses or pockets 8 are provided so as to afford good opportunity for a substantially spot weld at these places.

Having thus described my invention what I claim and desire to secure by Letters Patent is—

1. A two-piece welded brake shoe consisting of a shoe back having a steel concaved seat face, and a shoe-face plate seated on said shoe back and having a corresponding adjacent curved surface fitting the concavity of the shoe back, the shoe back having recessed edges and the shoe back and shoe-face plate spot welded together in these recesses, substantially as described.

2. A two-piece welded brake shoe consisting of a shoe back having a steel concaved seat face, a shoe-face plate having a steel convexed surface adapted to fit and conform to the concavity of the shoe back; the shoe-face plate having end flanges between which the shoe back fits, and said shoe back and shoe-face plate of substantially the same width to support the latter, the shoe back having recessed edges and the shoe back and shoe-face plate spot welded together in these recesses.

In testimony whereof I have hereunto set my hand in the presence of two subscribing witnesses.

JESSE M. YOUNT.
